UNITED STATES PATENT OFFICE

MAURICE ALLAND, OF ATLANTIC CITY, NEW JERSEY

BUTTON

Application filed January 16, 1929. Serial No. 332,877.

The object of this invention is to provide improvements in buttons, and particularly in that type which has for its general purpose the elimination of threads as a medium for securing buttons upon garments.

Many attempts have been made to design a button of this type which would prove satisfactory in every way, but practically if not every effort has been characterized by the endeavor to secure the button rigidly and non-rotatably as well as fixedly upon a garment, whereas there are serious objections to such a structure and none have met with favor, so far as is known.

15 In the buttoning of a garment, the part provided with the buttonhole tends to turn the button as the sides of the hole surround the periphery of the button, and while this movement has helped to cause the loosening 20 of the buttons secured by threads, it has been resisted by rigidly fixed buttons to such an extent as to cause dissatisfaction by users, with subsequent discarding of such buttons.

An object of the invention has therefore 25 been to provide a form of button which can be operatively secured to a garment without the use of threads and for such a length of time that it will long outwear the usefulness of the garment, and can then be detached and 30 transferred to another garment practically indefinitely, said button however being free to turn at all times, as when being inserted into a buttonhole, or as when the wearer of the garment absent-mindedly twists and 35 twirls the button from a nervous habit, or as a child does playfully.

Secondarily, it is the object of the invention to adapt the above-stated principle to buttons for use under different circumstances 40 and upon different types of garments, such as upon dress suits, business or sport suits, and upon uniforms both with plain and insignia-bearing surfaces.

With these and other objects in mind, the 45 present invention comprises further details of construction and operation which are fully brought out in the following description when read in conjunction with the accompanying drawings, in which Figs. 1 and 2 are 50 respectively a plan view and a diametrical

section of one embodiment of the invention; Figs. 3 and 4 are similar views of a modified form of the invention; Figs. 5 and 6 are similar views of a still further modification of the invention; and Figs. 7 and 8 are correspondingly similar views of still another modification of the invention.

Referring to Figs. 1 and 2 of the drawings, a button of any shape is shown as comprising a central disc portion 1, surrounded by a peripheral rim 2 and in turn surrounding a central portion which is characterized by a depending boss 3. Through said central portion extends a bore 4, which is enlarged at its upper end 5 and is adapted to rotatably receive the shank 6 of an attaching member, which to a certain extent resembles a bolt, a head 7 carried by said shank being positioned within the enlarged end portion 5 of the button's bore. Through a garment, represented by the dot-and-dash lines 8, an aperture is formed in any suitable manner, and through this aperture there extends the threaded end portion 9 of said shank, after which a preferably knurled nut 10 is attached to said threaded portion and turned thereupon, until the intervening portion of the garment material is firmly compressed between said nut and the adjacent surface 11 of the button boss 3, the member 6 being rotated with respect to the nut 10 by frictional engagement of one's finger with the head 7 or otherwise as may be desired, such for instance as by means of a screw driver engaging a slot or a spanner wrench engaging apertures or recesses within said head 7. With the button thus firmly attached to a garment, to all intents and purposes it is fixedly secured thereto, but is at all times free to rotate upon the shank 6 of the attaching member as when twirled by one's fingers, or when rotated during the insertion of the button through the buttonhole of another portion of the garment.

Referring to Figs. 3 and 4, the button here illustrated likewise comprises the central disc portion 1, peripheral portion 2, boss 3 having an end surface 11, bore 4, and enlarged portion 5 of said bore, said button being adapted for attachment to a garment

indicated by the dot-and-dash lines 8. The means whereby this button is secured to the garment is different from that illustrated in Figs. 1 and 2 in that it provides for widely differing thicknesses of garment material, without exposing any portion of the threaded button-engaging portion of the attaching member to the opposite side of the garment. In this case, a screw having a preferably knurled head 12, positioned within the bore enlargement 5, possesses also a threaded portion 13 of less diameter than the bore 4, said threaded portion being surrounded by the internally threaded portion 14 of a complementary screw which comprises also a head 15 positioned, as shown in Fig. 4, upon that side of the garment 8 opposite to the button, while the outer surface 16 of the threaded portion 14 is in slideable engagement with the cylindrical surface of the bore 4. In this construction, as that hereinbefore described, the button is fixedly attached, as shown in Fig. 4, to a garment, but is at all times adapted to rotate without in any way loosening its degree of attachment.

Referring to Figs. 5 and 6, there is shown a button having a metal or other exposed surface of a type which prevents the use of an exposed attaching member such as in the case of the heads 7 and 12 hereinbefore described. In this form of the device, a button disc 17 is provided with an axial bore 18, which extends also through a boss 19 and merges downwardly into a restricted bore 20. Within the bore 18 is positioned the head 21 of a member which is also provided with a threaded reduced extension 22, adapted to enter the threaded bore 23 of an upwardly extending boss 24, comprising a portion of a complementary attaching member also having a head 25, which is positioned upon that side of the garment 8 opposite to the button, said boss 24 being rotatable within the restricted portion 20 of the button's bore in a manner similar to that illustrated in Fig. 4. The outer surface of the button disc 17 is covered by any desired form of material 26 of any shape or configuration, secured to said disc in any suitable manner whatsoever, as by means of the radially inturned circumferential flange 27.

As the exposed surface of the button disc 17 is covered in such manner as to directly prevent manual engagement with the head 21 of the attaching means, it is necessary to provide said head with a transversely extending bore 28, which may be registered with aligned bores 29 in the opposite sides of the boss 19, so that an ordinary pin or needle may be inserted through said bores when in alignment, thereby permitting rotation of the button to unloosen the attaching head 21 with respect to the complementary member 24, as without the use of a pin or similar device the button 25 is freely rotatable with respect to said head.

In each of these three types of buttons just described, the part of the garment provided with the buttonhole adapted to receive the button surrounds the shank 3 of Figs. 2 and 4 and shank 19 of Fig. 6 and in inserting any one of these buttons through said buttonhole, the button is free to turn with respect to its attaching means and to the adjacent portion of the garment 8 and the sides of the buttonhole itself. Also, both before entering said buttonhole and at all times thereafter, the button itself may be freely rotated or oscillated without in any way loosening its mode of attachment to the garment 8.

Referring now to Figs. 7 and 8, there is shown a button bearing an insignia 30, which from its very nature should not at any time be inverted, wherefore this insignia is found supported by a button disc 31, having a boss 32, from which depend any suitable form of spaced spurs 33, which are adapted to be drawn directly into the material of the garment 8 as frictional or other engagements of the head 34 of an attaching bolt or the like rotates its threaded shank 35 into a correspondingly threaded bore 36 within the boss 32 of the button.

Thus, there has been provided a series of buttons designed to fulfill substantially, if not all of, the requirements of the garment industry and possessing the features which have been broadly stated in the above objects and which are also broadly specified in the claims appended thereto.

Having thus described my invention, what I claim and desire to protect by Letters Patent of the United States is:—

1. The combination of a button having a bore, with a boss on said button through which said bore extends and provided with aligned apertures, and interengaging male and female members rotatably positioned and overlapping each other within said bore, a portion of one of said members being provided with an aperture adapted when in alignment with said boss apertures to receive means to permit the relative turning and separation of said members by manual engagement with said button.

2. A button comprising a disc portion having a central boss and an axial bore, means to cover one end of said bore, the opposite end of said bore in said boss being of less diameter, and the walls of said boss being provided with an aperture, interengaging male and female members normally threaded together and extending through and in rotatable engagement with said bore, one of said members having a head within the larger part of said bore provided with an aperture adapted to register with said boss aperture, and the other of said members being provided with a head which serves to bind the material of a garment to said button, said button

normally being freely rotatable with respect to said attaching member, and when an instrument is inserted through said boss aperture and said head aperture, said members being relatively rotatable and separable by manual engagement of said button and the head of the second of said members.

5 In testimony whereof I have affixed my signature.
